(57) **CLAIM**

The ornamental design for a dishwasher basket, as shown and described.

DESCRIPTION

FIG. 1 is a top front perspective view of a dishwasher basket showing my new design;

FIG. 2 is a front view thereof;

FIG. 3 is a rear view thereof;

FIG. 4 is a right side view thereof, with the left side view being a mirror image;

FIG. 5 is a top view thereof;

FIG. 6 is a bottom view thereof;

FIG. 7 is a bottom rear perspective view thereof;

FIG. 8 is a top front perspective view of a dishwasher basket showing a second embodiment of my new design;

FIG. 9 is a front view thereof;

FIG. 10 is a rear view thereof;

FIG. 11 is a right side view thereof, with the left side view being a mirror image;

FIG. 12 is a top view thereof;

FIG. 13 is a bottom view thereof; and,

FIG. 14 is a bottom rear perspective view thereof.

The dashed broken lines in the figures show portions of the dishwasher basket that form no part of the claimed design.

1 Claim, 14 Drawing Sheets
